MILTON E. PHILLIPS, OF LENA, ILLINOIS, ASSIGNOR TO HIMSELF AND
GEORGE WETZEL.

Letters Patent No. 72,675, dated December 24, 1867.

IMPROVEMENT IN THRESHING-MACHINES.

The Schedule referred to in these Letters Patent and making part of the same.

TO ALL WHOM IT MAY CONCERN:

Be it known that I, MILTON E. PHILLIPS, of Lena, in the county of Stephenson, and State of Illinois, have invented certain new and useful Improvements in Grain-Threshers and Separators, of which the following is a full, clear, and exact description, reference being had to the accompanying drawings, which make part of this specification, and in which—

Figure 1 represents a side elevation,

Figure 2 a plan view, and

Figure 3 a vertical longitudinal section through my improved machine at the line $z z$ of fig. 1.

The invention herein claimed consists in certain novel devices, by means of which the same machine may be used for threshing, separating, and cleaning grain, and for hulling clover or other seed.

In the accompanying drawings, which exemplify one convenient arrangement of mechanism for carrying out the objects of my invention, I have shown a stout frame, A, of suitable construction to receive the mechanism. An inclined driving-shaft, B, driven from a horse-power (or other suitable motor) is mounted centrally in the frame in suitable bearings. A gear-wheel, b, on this shaft drives a corresponding pinion, c, on a cross-shaft, c', carrying a spur-wheel, C C', on each end, outside the frame. These wheels drive small spur-pinions, d d', on the shaft of the threshing-cylinder D, provided with a suitable concave, D¹. Behind the cylinder a series of stationary rods or bars, e, is arranged lengthwise of the frame, and parallel to each other. A series of parallel rotating shafts or rakes, E, is arranged transversely beneath these bars, and provided with curved rods or beaters e', which rotate between the slats and carry the straw back to the straw-carrier. These rods have cranks, e'', on their ends, and are driven by a crank and pitman, e³, on each of the wheels C C'. A shaking-screene, F, is suspended beneath these rotating shafts or rakes E by parallel rods f, and vibrated longitudinally by means of a pitman, f', connected with an eccentric on a transverse shaft, G, driven by a crank and pitman from each of the wheels C C'. Another eccentric on this shaft vibrates a shaking-shoe, H, suspended beneath the screen. The return-board h on the rear end of the shoe is inclined forward, so as to leave a space, h², between the board and shoe for the blast. A trough, f², on the rear end of the screen, leads to an elevator, I, which extends forward to a point above the threshing-cylinder, for a purpose hereinafter shown. A trough, h¹, leads downward and forward from the rear end of the shoe to a revolving screen, J, covered with screens 1 2 3, of varying fineness, and rotated from the main gear-wheel b by means of an idle-wheel, B¹, gearing into a spur-wheel, j, on the forward end of the screen-shaft j¹. A fan, K, is enclosed in a suitable case, k, and driven by gearing from the screen-shaft. The fan is supplied with air through a longitudinal slit in the bottom of the fan-case, which opening is closed by a regulating-valve, s, turning on a pivot, so that it can be opened to the desired extent, and be held by a spring-detent, s¹, taking into notches on a wheel, s², on the valve-pivot. Suitable bins, L, are arranged beneath the revolving screen to receive and keep separate the different qualities of grain. A hulling-cylinder, M, and concave or case, m, are arranged beneath the threshing-cylinder. The hulling-cylinder is driven from the wheels C C' by spur-pinions, m', on each end of its shaft. To prevent the breaking of the hulling-cylinder or case by stones getting mixed with the clover, I cut away a section from the bottom of the casing and replace it by a cover, m¹, held up to its place by springs, m², which yield when a rigid obstruction is encountered, and permit it to escape. A bevel-pinion, R, on the screen-shaft j¹, drives a pinion, r, on a transverse shaft, r'. A bevel-wheel, r², on the outer end of this shaft, drives a small pinion, n, on a longitudinal shaft, N. A bevel-pinion on the front end of this shaft drives a pinion on the shaft of the elevator O, while a pinion, k¹, drives the fan. A pinion, p, on the rear end of this shaft, drives a pinion, p¹, on the shaft of the straw-carrier P, which has a joint, p², in its middle, (for convenience in packing for storage or transportation,) and is connected with the main frame by link-rods p³.

The operation of the machine is as follows: When used as a thresher and separator or cleaner, an attendant stands on the front apron or platform Q and feeds the bundles into the threshing-cylinder D, which separates the grain from the straw, when both pass back to the revolving rakes E. As the rake-teeth successively rise between the slats e they impart a quick jogging backward motion to the straw, which motion effectually shakes out the grain, which falls upon the shaking-screene F, which still further separates the chaff from the grain.

The latter falls through the screen upon the shaking-shoe H, and drops from its rear end upon the return-board h, being exposed during its descent to a blast from the fan K, which blows off the chaff. The straw falls from the rakes upon the straw-carrier P, which conveys it away to the stack. The heads and chaff from the screen F and shoe H are also blown upon the carrier. The sound grain is conducted through trough h to the revolving screen J, by which it is assorted according to size and plumpness, and dropped into the bins L, which are provided with sliding doors, in order that the grain may be readily removed. The revolving screen will also separate grass or other seed from the grain.

The arrows indicate the direction of the movement of the several parts.

For hulling and cleaning clover-seed, the heads are passed through the threshing-cylinder as before. The seed fall between the boards e, but the bottom of the screen F is covered with a solid plate or board, so that the seed, instead of falling through, pass into the elevator I through the trough f², and are returned to the front of the machine. The seed pass down the spout i into the hulling-cylinder m, which consists of a series of spiral vanes or beaters, rasped or roughened on their outer surfaces, to remove the hulls from the seed. The seed and hulls pass from the hulling-cylinder through the spout o into the elevator O, which discharges them through a trough, o¹, upon the shaking-shoe H, whence they fall on the return-board h, being winnowed in their descent by the blast from the fan, and are conducted into the bins L through the revolving screens J, as before described.

The parts may be thrown into or out of gearing in any proper well-known way, and their construction might be varied to some extent without departing from the spirit of my invention.

What I claim as my invention, and desire to secure by Letters Patent, is—

1. The combination, as described, with the threshing-cylinder D and stationary slats e, of the rotating rakes E, having their shafts connected at each end with the same gear-wheels which drive the threshing-cylinder.
2. The combination, substantially in the manner described, of the threshing-cylinder D, the parallel slats e, the rotating rakes E, the longitudinally-vibrating screen F, and the shaking-shoe H; with the fan K, for the purpose set forth.
3. The combination, as described, of the threshing-cylinder D with the hulling-cylinder M, whereby both are driven at each end from the same gear-wheels.
4. The combination, as described, of the spiral rasped surface beaters of the hulling-cylinder M with the yielding concave m.
5. The combination of the closed fan-case k with the adjustable regulating-valve s, controlled by the spring-detent s², as set forth.
6. The combination, substantially as described, of the threshing-cylinder D, the rotating rakes E, the vibrating-screen F, the shaking-shoe H, and the hulling-cylinder M, whereby they are all driven by the same counter-shaft.
7. The combination, with the hulling-cylinder M, of the vibrating-screen F and elevator I, all arranged and operating as described.
8. The combination, with the hulling-cylinder M, of the elevator O, the shaking-shoe H, the fan K, and the revolving screen J, all arranged and operating as described.

In testimony whereof, I have hereunto subscribed my name.

MILTON E. PHILLIPS.
